DESIGN FOR A SLIP

Esther Cadous, New York, N. Y.

Application December 2, 1940, Serial No. 96,987

Term of patent 7 years

To all whom it may concern:

Be it known that I, Esther Cadous, a citizen of the United States of America, residing in the city of New York, county of New York, and State of New York, have invented a new, original, and ornamental Design for a Slip, of which the following is a specification, reference being had to the accompanying drawing, forming part thereof.

Fig. 1 is a front view of a slip showing my new design.

Fig. 2 is a rear view thereof.

The characteristic feature of my design resides in the combination on the specific slip disclosed of the specific arrangement of contrasting fabric on the front and back thereof as shown.

I claim:

The ornamental design for a slip, substantially as shown and described.

ESTHER CADOUS.
